ELECTROLYTIC GAS GENERATOR

Myron Y. Eck, Niagara Falls, N. Y.

Application April 12, 1934, Serial No. 720,342

8 Claims. (Cl. 204—5)

My invention relates generally to an electrolytic gas generator, and particularly to a gas generator of this type which is suitable for generating either refrigerating or heating gases, and an important object of my invention is to provide a simple and efficient generator of the character described which is simple and reliable, and can be constructed and operated at comparatively low cost.

Other objects and advantages of my invention will be apparent from a reading of the following description in connection with the drawings wherein for purposes of illustration I have shown a preferred embodiment of my invention.

In the drawings:—

Figure 1 is a longitudinal vertical sectional view through the embodiment and including the electrical circuit thereof diagrammatically.

Figure 2 is a plan view of one of the metal electrodes.

Figure 3 is a plan view of another one of the electrodes.

Figure 4 is a diagrammatic representation of an application of the embodiment.

Figure 5 is a longitudinal vertical sectional view showing the mounting of one of the electrodes shown in Figure 3.

Referring in detail to the drawings, the numeral 5 generally designates the embodiment which comprises the longitudinally elongated cylindrical or other suitable form of metal casing 6 which has at one end on its upper side a gas outlet tube 7. It will be observed that the top of the casing slants from the lower end of the casing upwardly to the opposite end which has the gas outlet 7. The upper part of the gas outlet 7 projects into a vertical casing 8 which constitutes a trap having baffles 9 and 10 for separating the heavier condensed vapors from the lighter gas which is to be used for refrigerating or heating. The lighter useful gases pass upwardly through the gas outlet 11 on the top of the trap 8. The heavier condensed vapors after separation fall to the bottom of the trap and pass therefrom through the small pipe 12 which empties into the bottom of the casing 6 as indicated by the numeral 13. The refrigerating or heating chamber generally designated 14 in Figure 4 to which the lighter gas conduit 11 leads, returns the lighter gases after use, through the pipe 15 which leads into the bottom of the casing 6, at the point indicated by the numeral 16. By reason of this arrangement there is maximum economy in the use of the lighter useful gases and in the conservation of the separated heavier constituents, so that maximum efficiency is attained in the electrolysis of the fluids which are dissociated within the casing by the passage of a suitable electric current therethrough through the medium of two sets of electrodes.

Within the casing 6 is mounted a vertically spaced pair of metal rods 17, 18 which are connected at their ends directly to the ends of the metallic casing 6. Mounted to and between these rods are spaced disk electrodes A which are of suitable metal, such as copper, monel metal, and the like. The form of these electrodes A is clearly shown in Figure 2. Diametrically opposite edge portions are provided with notches 19, 20 which receive the rods 17, 18, respectively, and whereby the electrodes A are held in the angulated arrangement shown in Figure 1. The center of the plates A have a relatively large opening 21. By reason of the direct connection of the electrodes A with the conductive rods 17, 18, which are in turn directly connected with the metallic casing 6, one side of the secondary of the step-down transformer T may be directly connected to the casing 6 by the conductor 22 at the point 23. The primary of the transformer T is fed by 10 alternating current supply as indicated.

At approximately the center of the opposite ends of the casing 6 are bosses 24, 25 which mount porcelain insulators 26, 27 which are socketed to receive the opposite ends of support rods 28, 29 which have their inner ends socketed in a central insulator 30 as shown in Figure 1. The support rods 28, 29 and the central insulator 30 are located in the openings 21 in the electrode plates A and clear the same except the center one, so that no electrical engagement obtains between the rods 28, 29 and the electrode plates A.

Mounted in longitudinally spaced manner on the support rods 28, 29 and between and outside of the electrodes A are other metallic electrode plates B which are smaller in diameter and are supported on the rods 28, 29 by virtue of engagement of these rods with a hole 31 in the center of the plates B. The end ones of these plates B abut the porcelain insulators 26, 27 and the middle ones of these plates abut the central insulator 30 for greater support.

Electrical connection to the electrodes B is made through conductive rods 32, 33 which are mounted to the opposite ends of the casing 6 in insulator bushings located in suitable openings in the said ends of the casing 6. The conductive rod 32 is connected by means of the conductor 36 with one side of the thermostatically controlled switch S the opposite side of which is connected to the remaining end of the secondary of the transformer. Another conductor 37 is variably connected with the secondary of the said transformer, and to one side of the second thermostatically controlled switch S whose opposite side is connected by means of a conductor 38 to the conductive rod 33. In this manner the electrodes B are completely insulated from the casing 6 and from the electrodes A and are adequately energized. It is obvious that the pro-

vision of the thermostatically controlled switches S and S' permits partial operation of the generator according to the supply of gas desired.

Suitable electrolytes for the generation of refrigerating gas are aqua-ammonia and some free flowing gases, such as hydrogen or nitrogen, or sulphur dioxide and water and some inert gas, in the presence of some suitable catalyst such as ammonium chloride or ammonium sulphate or sodium sulphite or sodium bisulphite, and the like.

For generating a heating gas which condenses when it passes through a standard radiator system, an electrolyte composed of alcohol, water, and ammonium sulphate replaces the aqua-ammonia. When generating gas for heating purposes, the trap 8 is eliminated and is not used, as the condensation takes place in the radiator system, and is returned to the casing 6 through the pipe 15.

Although I have shown and described herein a preferred embodiment of my invention, it is to be definitely understood that I do not desire to limit the application of the invention thereto, and any change or changes may be made in material and structure and arrangement of parts, within the spirit of the invention and the scope of the subjoined claims.

What is claimed is:—

30. 1. An electrolytic gas generator comprising a casing having a generated gas outlet, horizontal conductors within said casing and electrically connected to said casing and supporting a plurality of longitudinally spaced first electrodes therebetween, insulated support means in said generator carrying a plurality of second electrodes arranged between the first-mentioned electrodes and insulated therefrom, and a suitable source of electrical energy connected to said second electrodes and to said casing.
35. 2. An electrolytic gas generator comprising a casing having a generated gas outlet, horizontal conductors within said casing and electrically connected to said casing and supporting a plurality of longitudinally spaced first electrodes therebetween, insulated support means in said generator carrying a plurality of second electrodes arranged between the first-mentioned electrodes and insulated therefrom, and a suitable source of electrical energy connected to said second electrodes and to said casing, and a gas trap for separating lighter from heavier portions of the generated gas, said trap being connected to said casing for returning the condensed heavier portions into the casing, said trap being fed by the generated gas outlet.
40. 3. An electrolytic gas generator comprising a casing having a generated gas outlet, horizontal conductors within said casing and electrically connected to said casing and supporting a plurality of longitudinally spaced first electrodes therebetween, insulated support means in said generator carrying a plurality of second electrodes arranged between the first-mentioned electrodes and insulated therefrom, and a suitable source of electrical energy connected to said second electrodes and to said casing, the first electrodes being circular plates, and the second-mentioned electrodes being relatively smaller circular plates.
45. 4. An electrolytic gas generator comprising a casing having a generated gas outlet, horizontal conductors within said casing and electrically connected to said casing and supporting a plurality of longitudinally spaced first electrodes therebetween, insulated support means in said generator carrying a plurality of second electrodes arranged between the first-mentioned electrodes and insulated therefrom, and a suitable source of electrical energy connected to said second electrodes and to said casing, a generated gas outlet at one end of said casing, the top of the casing inclining upwardly in the direction of said gas outlet.
50. 5. An electrolytic gas generator comprising a casing having a generated gas outlet, horizontal conductors within said casing and electrically connected to said casing and supporting a plurality of longitudinally spaced first electrodes therebetween, insulated support means in said generator carrying a plurality of second electrodes arranged between the first-mentioned electrodes and insulated therefrom, and a suitable source of electrical energy connected to said second electrodes and to said casing, a gas outlet at one end of said casing, said first and second electrodes being inclined with respect to the horizontal so as to direct the generated gas upwardly and in the direction of said one end of the casing.
55. 6. An electrolytic gas generator comprising a casing having a generated gas outlet, horizontal conductors within said casing and electrically connected to said casing and supporting a plurality of longitudinally spaced first electrodes therebetween, insulated support means in said generator carrying a plurality of second electrodes arranged between the first-mentioned electrodes and insulated therefrom, and a suitable source of electrical energy connected to said second electrodes and to said casing, a gas outlet at one end of said casing, the top of the casing inclining upwardly in the direction of said gas outlet.
60. 7. An electrolytic gas generator comprising a casing having a generated gas outlet, horizontal conductors within said casing and electrically connected to said casing and supporting a plurality of longitudinally spaced first electrodes therebetween, insulated support means in said generator carrying a plurality of second electrodes arranged between the first-mentioned electrodes and insulated therefrom, and a suitable source of electrical energy connected to said second electrodes and to said casing, a generated gas outlet at one end of said casing, the top of the casing inclining upwardly in the direction of said gas outlet.
65. 8. An electrolytic gas generator comprising a casing having a generated gas outlet, horizontal conductors within said casing and electrically connected to said casing and supporting a plurality of longitudinally spaced first electrodes therebetween, insulated support means in said generator carrying a plurality of second electrodes arranged between the first-mentioned electrodes and insulated therefrom, and a suitable source of electrical energy connected to said second electrodes and to said casing, a generated gas outlet at one end of said casing, the top of the casing inclining upwardly in the direction of said gas outlet, and said first and second electrodes being acutely angulated with respect to the horizontal so as to direct the generated gas upwardly and in the direction of said gas outlet.

10. 9. Longitudinally spaced first electrodes therebetween, insulated support means in said generator carrying a plurality of second electrodes arranged between the first electrodes and insulated therefrom, a suitable source of electrical energy connected to said second electrodes and to said casing, the first electrodes being circular plates, and the second electrodes being relatively smaller circular plates, and thermostatically controlled switch means interposed between said source of electrical energy and said first and second electrodes, said switch means being exposed to heat or cold in the system being supplied with refrigerant gas or with heating gas, as the case may be.

15. 10. An electrolytic gas generator comprising a casing having a generated gas outlet, horizontal conductors within said casing and electrically connected to said casing and supporting a plurality of longitudinally spaced first electrodes therebetween, insulated support means in said generator carrying a plurality of second electrodes arranged between the first-mentioned electrodes and insulated therefrom, and a suitable source of electrical energy connected to said second electrodes and to said casing, said first and second electrodes being arranged at acute angles to the horizontal.

20. 11. An electrolytic gas generator comprising a casing having a generated gas outlet, horizontal conductors within said casing and electrically connected to said casing and supporting a plurality of longitudinally spaced first electrodes therebetween, insulated support means in said generator carrying a plurality of second electrodes arranged between the first-mentioned electrodes and insulated therefrom, and a suitable source of electrical energy connected to said second electrodes and to said casing, a gas outlet at one end of said casing, said first and second electrodes being inclined with respect to the horizontal so as to direct the generated gas upwardly and in the direction of said one end of the casing.

25. 12. An electrolytic gas generator comprising a casing having a generated gas outlet, horizontal conductors within said casing and electrically connected to said casing and supporting a plurality of longitudinally spaced first electrodes therebetween, insulated support means in said generator carrying a plurality of second electrodes arranged between the first-mentioned electrodes and insulated therefrom, and a suitable source of electrical energy connected to said second electrodes and to said casing, a generated gas outlet at one end of said casing, the top of the casing inclining upwardly in the direction of said gas outlet.

30. 13. An electrolytic gas generator comprising a casing having a generated gas outlet, horizontal conductors within said casing and electrically connected to said casing and supporting a plurality of longitudinally spaced first electrodes therebetween, insulated support means in said generator carrying a plurality of second electrodes arranged between the first-mentioned electrodes and insulated therefrom, and a suitable source of electrical energy connected to said second electrodes and to said casing, a generated gas outlet at one end of said casing, the top of the casing inclining upwardly in the direction of said gas outlet, and said first and second electrodes being acutely angulated with respect to the horizontal so as to direct the generated gas upwardly and in the direction of said gas outlet.
